W. A. McELROY,
ATTACHMENT FOR ARTIFICIAL ARMS,
APPLICATION FILED AUG. 31, 1921.

1,417,267.

Patented May 23, 1922.

INVENTOR
WILLIAM A. McELROY

BY ATTORNEY

Lincoln Johnson

UNITED STATES PATENT OFFICE.

WILLIAM A. McELROY, OF SAN FRANCISCO, CALIFORNIA.

ATTACHMENT FOR ARTIFICIAL ARMS.

1,417,267.

Specification of Letters Patent. Patented May 23, 1922.

Application filed August 31, 1921. Serial No. 497,091.

To all whom it may concern:

Be it known that I, WILLIAM A. McELROY, a citizen of the United States, and a resident of the city and county of San Francisco, State of California, have made a new and useful invention—to wit, Improvements in Attachments for Artificial Arms; and I do hereby declare the following to be a full, clear, concise, and exact description of the same.

This invention relates particularly to an artificial limb.

An object of this invention is to provide a mechanical substitute for the fingers and hand, which may be operatively applied to an artificial limb, that will operate substantially in the same manner as the fingers and hand of a human being. A further object of the invention is to provide an artificial limb that may be readily adjustable to any number of predetermined positions. A further object is to provide an artificial limb that will be superior in point of simplicity, inexpensiveness of construction, positiveness of operation, facility and convenience in use and general efficiency. Other objects and advantages will appear as this description progresses.

In this specification and the annexed drawings, the invention illustrated is the form considered to be the best, but it is to be understood that the invention is not limited to such form, because it may be embodied in other forms; and it is also to be understood that in any of the claims following the description, it is desired to cover the invention in whatsoever form it may be embodied.

In the accompanying one sheet of drawings:

Figure 1 is a side elevation partly broken away to illustrate an artificial limb constructed in accordance with my invention.

Figure 2 is a plan view of Figure 1.

Figure 3 is a plan view of the under side of Figure 1.

Figure 4 is a vertical section taken through Figure 1 on the line 4—4.

In the manufacture of artificial limbs, more particularly of mechanical substitutes for the fingers and hand on an artificial arm, it has been found extremely difficult to provide a satisfactory substitute whereby the wearer might use the mechanical contrivance in the same manner as the real fingers and hand. My invention contemplates a me-

chanical construction of an artificial hand which will, in a measure, permit of the same uses as the human hand and in detail the construction illustrated in the drawings 60 comprises an arm or supporting member 1. The supporting member 1 is diagrammatically illustrated so as to represent any general type or form of artificial arm and which, in this particular instance, is 65 composed of a substantially cylindrical body having a peripheral collar 2 around the open end thereof. A plate 3 is provided within the cylindrical body 1 and approximately closing the open end of the said body. A 70 plate 4 is provided within the interior of the body and fixedly secured thereto. Compression spring 5 is mounted within the body and between the plates 3 and 4 and normally tends to press or force the plate 3 75 outwardly in contact with the collar 2. Each of the plates 3 and 4 is provided with concentric openings as at 6 and 7, the said opening 7 being enlarged to receive the slotted bushing 8, the edge of which projects beyond 80 the plate 4 and is serrated as shown at 9.

The hook member 10 has a shaft 11 thereon, substantially of the same diameter as the openings 6 and 7, and which is adapted to pass therethrough. To hold the hook 85 member 10 and supporting member 1 in operative position the shaft 11 is provided with a projection 12 on the end thereof which is adapted to register with and pass through the slotted portion of the bushing 90 8 when placed in engagement therewith. After the projection 12 passes beyond the slot in the interior of the body portion of the member 1, the shoulder 14 on the hook member 10 adjacent the shaft 11 engages 95 the movable plate 3 and tends to compress spring 5, at which juncture shaft 11 would be rotated so as to move the projection 12 thereon in engagement with the serrated edge of the bushing 8 in which position it 100 would be securely locked through the compressive action of the spring 5, indirectly bearing against the hook shoulder 14. The hook member 10 is a relatively stationary element and between the curved terminus 15 105 thereof and the shaft 11, it is slotted as at 16 intermediate the side walls 17 and 18. The slotted portion 16 is preferably a uniform passageway between the parallel sides 17 and 18. The side walls 17 and 18 are 110 formed on a radial curvature and each of the side walls 17 and 18 have aligned radial

slots 19 cut therein on a predetermined radius. A companion or relatively movable hook member 20 with a suitable terminus 21 is adapted to be mounted in juxtaposition 5 to the hook 10 and which has the flattened, end 22 thereof made of a thickness slightly less than the slot 16 whereby said end 22 may be slidably mounted in the aforementioned position. A suitable pivot pin 23 10 fixed in the shaft end terminus of the hook member 10 is adapted to pass through a pivot hole in the flattened end 22 of the hook 20 whereby each of said hooks will be maintained in pivotal relation and it becomes 15 possible to move one of the hook members relative to the other. The flattened end of the hook member 20 is provided with a radial slot 24 therein normally eccentric to the slots 19 and in partial registry therewith.

The end of the flattened portion 22 of the hook member 20 is provided with a projecting arm 26 thereon and through the end of which the stud shaft 27 passes, said shaft 25 having the rollers 28 and 29 freely mounted thereon on opposite sides of the arm 26. A U-shaped or yoke member 30 is provided with spaced arms 31 and 32 that are adapted to straddle the side walls 17 and 18 whereby 30 the ends 33 and 34 of said yoke member 35 may be pivotally engaged with the ends of the stud shaft 27. A cross-pin 35 is adapted to pass between the sides 31 and 32 of the yoke 30 and to which the looped ends of the coil springs 36 and 37 are secured, said 40 springs passing around the rollers 28 and 29 and having the opposite ends thereof secured to the cross pin 36 mounted in the flattened end 22 of the hook member 20. It is desirable that the springs 36 and 37 be normally under sufficient tension so as to hold the bridge portion of the yoke 30 in frictional contact with the upper edge of the hook member 10 as shown in Figure 1. 45 Between the bridge portion 30 of the yoke member and the ends 33 and 34 thereof, a cross shaft 40, having a roller 41 thereon, has its opposite ends journaled in the side members 31 and 32 of the said yoke, and in 50 alignment with the partially registering slots 19 and 24 in the hook members 10 and 20. The exterior of the bridge portion of the yoke 30 is suitably finished to permit a cable or the like being securely fastened 55 thereto for the purpose of moving the said yoke member 30 and thus moving the hook members 10 and 20 in any predetermined or desirable position.

In the actual operation of this invention 60 the wearer of the artificial limb would have a cord 42 secured to the bridge end of the yoke 30 which would be grasped when it would be desired to separate the superficially contacting termini 15 and 21 of the 65 hook members 10 and 20. Movement of the

hook members 10 and 20 relative to each other is accomplished by moving the yoke 30 about the stud shaft 27, which results in moving the roller shaft 40 proportionately between the eccentrically positioned radial slots 19 and 24. The shaft 40 thus acts as a cam and apertures 19 and 24 as cam slots whereby movement of the said cam element 40 relative to the slots, registers predetermined portions thereof and elevates 75 or lowers the hook members 10 and 20 according to the position of the cam 40 relative to the radial slots 19 and 24. Any movement whatsoever of the yoke 30 is against the tension of the springs 36 and 37, said spring means acting on the yoke 30, shaft 40 and radial slots 19 and 24 for normally maintaining each of the hook termini in superficial contact.

To illustrate the operation of the invention the yoke 30 would be moved radially about its pivot axis 27 spreading the hooks 10 and 20 in direct proportion. An article to be grasped would then be positioned between the hooks 10 and 20 and the said hooks allowed to come together (due to the spring action) in which position the article would be grasped and securely held. Once an article is positioned between the hook members 10 and 20, it would be impossible 95 to withdraw it therefrom inasmuch as spreading action of the hook members 10 and 20 would tightly wedge against the yoke 30 and thus be tightly locked. As a result the cam action of the shaft 40 and the 100 slots 19 and 24 automatically controls the separation or coming together of the hook members 10 and 20 in contra-distinction to various known artificial appliances tended to function in a similar manner wherein the 105 hook or jaw members are separated manually.

What I claim and desire to secure by Letters Patent is:

1. A device such as described comprising 110 a supporting member; a hook member having a radial slot therein connected to said supporting member; an auxiliary hook member having a radial slot therein, placed in juxtaposition to said first mentioned hook 115 member, and pivotally connected thereto; and a cam, pivotally connected to one of said hook members and operatively arranged in the slots in each of said hook members, for moving one of said hooks relative to the 120 other.

2. A device such as described comprising a supporting member; a hook member having a radial slot therein connected to said supporting member; an auxiliary hook member 125 having a radial slot therein, placed in juxtaposition to said first mentioned hook member, and pivotally connected thereto; a cam, pivotally connected to one of said hook members and operatively arranged in the slots 130

in each of said hook members, for moving one of said hooks relative to the other and spring means for normally maintaining each of said hooks in superficial contact.

- 5 3. A device such as described comprising a supporting member; a relatively stationary hook member connected to said supporting member; and having a radial slot therein; a movable hook element pivotally connected to said first mentioned hook member, in juxtaposition therewith, and having a radial slot therethrough each of said slots being mounted eccentrically relative to each other; and means, pivotally connected to one 10 of said hook members having an extended portion passing through said slots, adapted to move one of said hooks relative to the other.
4. A device such as described comprising 20 a supporting member; a relatively stationary hook member connected to said supporting member, and having a radial slot therein; a movable hook element pivotally connected to said first mentioned hook member, in juxtaposition therewith, and having a radial slot therethrough each of said slots being mounted eccentrically relative to each other; means pivotally connected to one of 25 said hook members having an extended portion passing through said slots, adapted to move one of said hooks relative to the other and spring means for normally maintaining each of said hooks in superficial contact.

5. A device such as described comprising 35 a supporting member; a relatively stationary hook member, connected to said supporting member, having a radial slot therethrough, a movable hook element pivotally connected to said first mentioned hook mem-

ber, in juxtaposition therewith, and having 40 a radial slot therethrough, each of said slots being mounted eccentrically relative to each other and in partial registry; a cam arm pivotally mounted on one of said hook elements and having a portion thereof passing 45 through said axial slots adapted to move one of said hooks relative to the other and spring means for normally maintaining each of said hooks in superficial contact.

6. A device such as described comprising 50 a supporting member; a hook member adjustably connected to said supporting member; an auxiliary hook member pivotally connected to said first mentioned hook member in juxtaposition therewith; a cam 55 arm pivotally mounted on one of said hook members and eccentrically engaging each of said hook members for moving each of said hook members relative to the other.

7. A device such as described comprising 60 a supporting member; a hook member adjustably connected to said supporting member; an auxiliary hook member pivotally connected to said first mentioned hook member in juxtaposition therewith; a cam arm 65 pivotally mounted on one of said hook members and eccentrically engaging each of said hook members for moving each of said hook members relative to the other and spring means for normally maintaining each of 70 said hooks in superficial contact.

In testimony whereof, I have hereunto set my hand at San Francisco, California, this 26th day of August, 1921.

WILLIAM A. McELROY.

In presence of—
LINCOLN V. JOHNSON.
